STRAINER UNIT FOR TOILETS

Charles Lundelius, 7609 Twin Oaks Ave.,
Citrus Heights, Calif.

Filed Apr. 16, 1959, Ser. No. 806,913

4 Claims. (Cl. 4—257)

This invention relates to, and it is a major object to provide, a novel strainer unit adapted for use in a toilet bowl for the purpose of permitting diapers or the like to be rinsed—in said bowl—free of fecal matter or other waste without possibility of the diapers entering the waste outlet passage of the toilet and plugging it or the disposal line to which the toilet delivers.

Another important object of the invention is to provide a strainer unit, as above, which is arranged so that after initial rinsing of the diapers in the bowl, the toilet can be flushed to carry away the waste material while at the same time preventing the diapers—which then remain in said bowl—from being flushed away.

An additional object of the invention is to provide a strainer unit, for the purpose described, which is normally detached from the toilet, but which unit can be readily and conveniently removably engaged in the toilet bowl in covering relation to the waste outlet opening; there being novel means included in the strainer unit to maintain the same in place in said bowl.

It is also an object of the invention to provide a strainer unit for toilets which is designed for ease and economy of manufacture.

Still another object of the invention is to provide a practical, reliable, and durable strainer unit for toilets, and one which will be exceedingly effective for the purpose for which it is designed.

These objects are accomplished by means of such structure and relative arrangement of parts as will fully appear by a perusal of the following specification and claims.

In the drawings:

Fig. 1 is a vertical front to rear sectional elevation of a toilet showing the strainer unit in side elevation and in place in the toilet bowl.

Fig. 2 is an enlarged front elevation of the strainer unit as in place; the view including a fragmentary showing of the bowl, partly in section.

Fig. 3 is a vertical section of the strainer unit detached, and taken on line 3—3 of Fig. 2.

Referring now more particularly to the drawings, and to the characters of reference marked thereon, the strainer unit, indicated at 1, is adapted for use in a conventional toilet which includes a bowl 2 and a water tank 3 having a valve 4 which controls water flow from tank 3 to the water inlet passage 5 of said bowl.

The bowl 2, as usual, embodies a bottom 6, sides 7, a back wall 8, and a circular waste outlet opening 9 in back wall 8 immediately adjacent the bottom 6. The lower portions of sides 7 have reduced transverse spacing to form, in effect, a trough directly ahead of said waste outlet opening 9. The waste outlet opening 9 communicates with a waste outlet passage 10 of gooseneck or trap form, which passage 10 connects, through the base of the toilet, with the disposal line 11.

The strainer unit 1, which embodies the present invention, is a relatively small, portable device comprised of a frame, indicated generally at 12, which frame in-

2

cludes, at its lower end, a transverse foot 13 of very heavy material, such as lead; the lower edge of such foot being curved to seat in substantially matching relation on the bottom 6 of the bowl 2 immediately in front of the waste outlet opening 9.

In addition to the transverse foot 13 the frame 12 includes an upstanding, inverted, generally horse-shoe shaped wire or rod 14 which is continuous and whose lower ends are embedded in the corresponding end portions of the transverse foot 13.

Within the confines thereof, the frame 12 is fitted with a screen 15 having a relatively large mesh; such screen, at its lower end, being embedded in the transverse foot 13, and thereabove such screen is secured at its edge—in any suitable manner—to the rod 14.

The assembly of frame 12 and screen 15 is vertically concavo-convex with the concave side rearmost.

A spring finger 16 projects rearwardly from substantially centrally of the screen 15; said spring finger 16 including, at its inner end, a down-turned attachment ear 17 which is fixed to the screen 15. At its outer end the spring finger 16 has a down-turned lip 18.

A relatively long, ball-link chain 19 is connected at one end to the outside of the screen 15 immediately opposite the attachment ear 17; such chain 19 being of a length to extend from within the bowl 2, at a point adjacent the waste opening 9, to a point exteriorly of the bowl after passing over the rim 20.

When it is desired to use the above described strainer unit 1, the bowl 2 is first flushed and filled with clean water, and thereafter said unit is placed in the bowl 2 in the position illustrated in Fig. 1; i.e., upstanding from the bowl bottom 6 in front of, and extending above, the waste outlet opening 9, and at a slight upward and

rearward incline. With the strainer unit 1 so disposed in the bowl 2, the transverse foot 13 rests in substantially matching engagement with the bowl bottom 6, while corresponding portions of the frame rod 14 substantially matchingly engage the lower portions of the sides 7 and the adjacent part of the back wall 8; the highest point of engagement with the back wall being a distance above the waste outlet opening 9.

Upon the strainer 1 being manually moved to position in the bowl 2, as above described, the spring finger 16 enters the waste outlet opening 9 at the top of the latter and comes to rest in frictional holding engagement under the edge of the back wall 8 at the top of said opening, as at 21. The down-turned lip 18 of spring finger 16 serves to cam said finger into its holding position, as above described.

In addition to the action of said spring finger 16 in holding the strainer unit 1 in place in the bowl for use, the foot 13—of lead—also has a stabilizing effect because of its weight.

When the strainer unit 1 is in place in the bowl 2, the chain 19 extends out of said bowl, over the rim 20, and depends from the latter.

With the strainer unit 1 mounted in its position of use, such unit effectively covers the waste outlet opening 9. Diapers can then be initially rinsed in the water 22 in bowl 2, and thereafter such water, and the waste material carried therein, can be flushed from the toilet through the opening 9 and passage 10 without the possibility of the diapers entering and plugging said opening or passage, yet without restricting the flushing-away of the waste material with the water, and which material passes freely through the large mesh of screen 15.

After several additional flushings of the toilet—and which further rinses the diapers in the bowl 2—such diapers are manually removed from the bowl.

Thereafter, by the simple expedient of pulling on the

chain 19, the strainer unit 9 can be detached and removed from the bowl, so that the toilet then remains unobstructed for normal use.

While the strainer unit 1 is here shown and described as used in a toilet having the waste outlet opening 9 in the rear of the bowl, such unit is equally adaptable to a toilet of the type wherein said opening is in the front of the bowl.

From the foregoing description it will be readily seen that there has been produced such a device as will substantially fulfill the objects of the invention, as set forth herein.

While the specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

I claim:

1. A strainer unit for a toilet, such toilet including a bowl having a bottom and an upstanding wall thereabout, and the bowl having a waste outlet opening the upper edge of which is in said wall above the bottom; the strainer unit comprising an endless rigid frame shaped to fit in the bowl in a plane transversely parallel to the outlet opening and to then engage said bowl bottom and the upstanding wall in clearance relation to and about the opening, a large-mesh screen secured to and surrounded by the frame, and means on the unit adapted to engage the bowl in releasable holding relation to retain the frame in place; said means comprising a spring finger secured to and projecting from the unit intermediate the upper and lower edges thereof and adapted to extend through the outlet opening and frictionally engage the bowl wall within and at the upper edge of said opening.

2. A unit, as in claim 1, with a flexible pull-element

connected at one end to the front of the screen adjacent the point of connection of the finger therewith; said element being of a length such as to enable it to extend, when slack, from said one end thereof to and over the rim of the bowl at one side thereof and to then hang down a material distance from said rim.

3. A strainer unit for a toilet, such toilet including a bowl having a bottom and an upstanding wall thereabout, and the bowl having a waste outlet opening the upper edge of which is in said wall above the bottom; the strainer unit comprising an endless rigid frame shaped to fit in the bowl in a plane transversely parallel to the outlet opening and to then engage said bowl bottom and the upstanding wall in clearance relation to and about the opening, a large-mesh screen secured to and surrounded by the frame, and means on the unit adapted to engage the bowl in releasable holding relation to retain the frame in place; the frame including a transversely extending weighted foot along its lower edge shaped to follow the contour of and engage the bottom of the bowl.

4. In combination, a toilet bowl having a bottom and an upstanding wall thereabout, the bowl having a waste outlet opening the upper edge of which is in said wall above the bottom, a strainer unit comprising an endless rigid frame of larger area than said opening supported on the bottom of the bowl and upstanding about the opening, and a large-mesh screen secured to and surrounded by the frame; and an element on said unit releasably engaging the bowl and retaining the unit in place.
